Primary Examiner — Lakiya G Rogers*Assistant Examiner* — Carissa C Fitts(74) *Attorney, Agent, or Firm* — Manatt, Phelps & Phillips LLP(57) **CLAIM**

The ornamental design for an illumination device for a horse, as shown and described.

DESCRIPTION

FIG. 1 is a front perspective view of the illumination device for a horse showing a new design;

FIG. 2 is an enlarged front perspective view of a portion thereof;

FIG. 3 is an enlarged front elevation view thereof;

FIG. 4 is an enlarged back elevation view thereof;

FIG. 5 is an enlarged right side view thereof;

FIG. 6 is an enlarged left side view thereof;

FIG. 7 is a bottom plane view thereof; and,

FIG. 8 is a top plane view thereof.

The broken lines shown in all views represent unclaimed subject matter and form no part of the claimed design.

1 Claim, 5 Drawing Sheets(56)
